FIG.1

FIG.2

FIG.3

FIG.4

FIG.5

FIG.6

FIG. 1 is a side elevation showing a mobile antenna mount incorporating my new design, with an antenna whip base and a support here shown fragmentarily in phantom but omitted in the other figures;

FIG. 2 is a front elevation of the mobile antenna mount shown in FIG. 1;

FIG. 3 is a plan view of the mobile antenna mount shown in FIG. 1;

FIG. 4 is a rear elevation of the mobile antenna mount shown in FIG. 1;

FIG. 5 is a bottom view of the mobile antenna mount shown in FIG. 1; and

FIG. 6 is a perspective view of the mobile antenna mount shown in FIG. 1, taken from the left front and slightly above.

The portions shown in phantom in the drawings are included for completeness of a showing of the mobile antenna mount but form no portion of my new design.

I claim:

The ornamental design for a mobile antenna mount, as shown and described.
